VULCANIZING PRESS AND TIMING MECHANISM THEREFOR

Leslie E. Soderquist, Akron, Ohio, assignor to The McNeil Machine & Engineering Company, Akron, Ohio, a corporation of Ohio

Application September 26, 1940, Serial No. 358,441

6 Claims. (Cl. 18—17)

This invention relates to vulcanizing presses and to timing mechanism for use therewith, and more particularly it relates to such mechanism as used with presses for curing inner tubes for pneumatic tires. The timing mechanism is illustrated and described in connection with tube presses, but it may also be employed in presses for curing tires and other articles.

In using vulcanizing presses of the type referred to it is customary to vulcanize the tube or other article between upper and lower mold sections which are heated, preferably by steam jackets. The interior of the article is connected to a source of hot air (and in some cases steam) which assists the heat in the jacket in curing the article.

It is an object of this invention to improve upon existing presses and timing mechanism and to secure new and beneficial results as will be more fully set forth. The press disclosed in this application is fully automatic, it being necessary only to start the press in operation after an article has been properly placed therein, and the press will close, remain closed during the curing cycle and open again at the end of the cure.

Another object is to provide timing mechanism which will not only automatically control the opening and closing of the press, the admission and exhaustion of fluid into and out of the article to be cured, the time of the cure, etc., but which will automatically return the timer to its starting position at the end of the cure whereby it will be instantly ready for the next article to be cured.

A further object is to provide safety means whereby if during the closing of the press any foreign object, such as an operator's arm, should be caught between the mold section, the closing movement is instantly stopped, and the movement may be reversed to return the press to open position.

A further object is to provide a timing mechanism which may be interrupted during its cycle of operation and upon such interruption will immediately and automatically return the timer to its starting position.

Other objects and advantages will become apparent from the following description taken in conjunction with the accompanying drawings.

In the drawings:

Fig. 1 is a side elevation of the press and timer with parts shown in section,

Fig. 2 is an enlarged vertical section taken substantially on line 2—2 of Fig. 4, with parts shown in elevation,

Fig. 3 is a similar view taken substantially on line 3—3 of Fig. 4.

Fig. 4 is a similar view taken substantially on line 4—4 of Fig. 2.

Fig. 5 is an enlarged horizontal section taken substantially on line 5—5 of Fig. 4.

Fig. 6 is a further enlarged fragmentary section taken substantially on line 6—6 of Fig. 2.

Fig. 7 is a similar fragmentary view taken substantially on line 7—7 of Fig. 6.

Fig. 8 is an enlarged section similar to the upper part of Fig. 4 with the parts shown in a different position than in Fig. 4.

Fig. 9 is an enlarged vertical section taken substantially on line 9—9 of Fig. 8, and

Fig. 10 is a diagrammatic view showing the preferred wiring diagram used with the apparatus.

Referring to the drawings the numeral 10 designates the stationary lower mold section of an inner tube vulcanizing press, while the upper movable mold section is indicated at 11. Both sections are steam jacketed as shown in Fig. 1, being connected to a suitable source of steam (not shown). While I have shown the lower mold section stationary and the upper mold section movable, this arrangement can be reversed or both sections may be movable, if desired. Lower mold section 10 contains a portion 12 of a tube molding cavity which receives a tube 13 to be vulcanized in the press. Upper mold section 11 has a complementary portion 14 of the tube molding cavity which, together with portion 12, completely enclose tube 13 when the mold sections are closed, and form a chamber in which the tube is treated or cured as is well known in this art. Inner tube 13 is connected through its valve stem 15 with a line 16 through which hot air or other inflating and curing fluid is admitted to the tube.

The lower mold section 10 is fixed upon a base 17 in which is pivoted the stationary shaft 18 which forms a fixed bearing for a lever actuating mechanism. On the ends of shaft 18 projecting beyond the frame of the base are two parallel pressure links 19 which extend upwardly on each side beyond the upper mold section and are pivoted at their upper ends, by bearing pins 20, to two parallel rocking arms or levers 21 which extend on both sides of the operating centers formed by the pins 20. One end of each lever 21 is connected by a transverse shaft 22 on which is pivoted a heavy platen 23. Levers 21 are connected to a heavy transverse web or bracing member 24 which serves to tie the levers together. Upper

mold section 11 is adjustably secured to platen 23 by means of suitable screws 25.

The opposite ends of each lever 21 carry pivot pins 26 by which these levers are connected to the upper end of a pair of parallel operating links 27, the lower ends of which are pivoted to pins 28 secured to crank arms 29 which are, in turn, formed integral with crank wheels 30. Wheels 30 are fixed to the ends of a main operating shaft 31 supported in the rear of the base 17. This shaft 31 is connected through suitable gearing (not shown) with a three phase driving motor 32, although any other suitable motor may be used, if desired.

As shown and described, the press actuating means are substantially identical with those shown in my copending application Serial No. 199,417, filed April 1, 1938, and reference may be had to said application for any further information desired concerning same.

Still referring to Fig. 1, a pair of spaced brackets 33 are carried by base 17 adjacent the front thereof and these brackets carry a post 34 that supports a timer box or housing 35 which carries the timing mechanism to be described, suitable securing means 36 being provided to secure the housing to the post. The top of housing 35 has an incoming fluid line 37 leading thereto from a suitable source of pressure (not shown), in which line there is a two way valve 38 and a hand operated valve 39, the latter ordinarily not being used. Valve 38 is normally closed when the press is open as in Fig. 1, and a spring pressed pin 40 is operated to open this valve. As shown, one of the side links 19 carries a spring pressed plunger 41 which engages pin 40 when the press is closed, as indicated by the dash line position of link 19 in Fig. 1, and permits passage of fluid through valve 38 into housing 35.

After passing through valve mechanism in housing 35 which will be later described, the fluid passes out of the housing into line 42 which leads to a diaphragm valve 43 of the conventional type, the latter valve being adapted to control the passage of hot air or other fluid under pressure to inner tube 13. It will be noted from Fig. 1 that this fluid which enters tube 13 passes through line 44 from a suitable source of pressure (not shown) to the lower end of valve 43, the upper end of which is connected to line 16 which leads to the tube. When valve 43 is open, fluid will pass from line 44 into tube 13, but when closed, this fluid will exhaust from tube 13 through a conventional exhaust port in valve 43.

Referring now to Fig. 4, it will be observed that housing 35 has a lower cored portion 45 which receives the upper end of post 34, the latter being hollow to receive a tube 46 through which the various conductor wires (not shown) for the different parts of the timing mechanism are brought into the housing. Above portion 45, the housing is provided with a compartment 47 having an opening 48 in its rear wall which is closed by a backing plate 49, a gasket 50 being arranged between plate 49 and the housing. Compartment 47 has a lower portion 51 in which is mounted a double arm type starting switch 52 for the timer motor to be described, a stop switch 53, and a reversing switch 54, all of which switches are conventional and whose operation can be readily understood from Fig. 10. Adjacent its upper end, housing 35 has the incoming line 37 and the outgoing line 42 passing therethrough and being received in the short front wall 55 (see Fig. 3), which wall is provided with ports 56 and 56' (see

Figs. 3 and 7) for the passage of fluid through the wall in a manner to be described.

The numeral 57 designates a closure member for the front of housing 35 which is secured thereto as at 58 (Figs. 2 and 3) and which is provided with a chamber 59 in its upper portion, while the lower portion of member 57 is reduced in width as at 60 so as to cover a similarly reduced lower portion of housing 35.

Chamber 59 has a rear wall 61 which extends the length of the chamber except for an opening 62 adjacent the top thereof and a smaller opening 63 at the bottom, both of which openings permit communication between compartment 47 and chamber 59. On opposite sides of opening 62, wall 61 is provided with preferably integral bracket arms 64 which extend into compartment 47, and lower projections 65 on the ends of these arms support the upper end of a plate 66, as by means of screws 67, in parallel relation with wall 61, the lower end of plate 66 being secured to the outer end of a supporting arm 68, also preferably formed integral with wall 61.

Wall 61 and plate 66 are provided with bearings 69 and 70, respectively, which slidably and rotatably receive a shaft 71 which has a gear 72 fixed thereon by a means of a pin 73, while spaced from this gear, a collar 74 is fixed on the shaft by a pin 75. Outwardly of wall 61, shaft 71 is reduced in size to receive a collar 76 which is keyed thereon as at 77 and which is provided with a rear flange 78. Collar 76 is also provided with a keyway 79 which receives a key 80 of a main cam disc 81, while between disc 81 and flange 78, a pair of cooperating cam discs 82 and 83 are mounted so as to turn on collar 76 except when fastened tightly between disc 81 and flange 78. Also mounted on collar 76, outwardly of disc 81, is a ring 84 having a small handle 85 which facilitates adjustment of the cam discs. Handle 85 has its inner end extending into keyway 79 and movement of ring 84 around collar 76 is therefore limited to the movement of handle 85 in keyway 79, except when tightened as will be explained. The outer end of shaft 71 is screw threaded as at 86 to receive a tightening nut 87 threaded thereon, which when tightened will hold ring 84, and discs 81, 82 and 83 between said nut and flange 78 whereby there will be no relative movement between any of these members and shaft 71. Nut 87 has a reduced hexagonal opening 87' therein for a purpose to be described. The outer end of nut 87 carries a push button 88 which is used to slide shaft 71 and everything connected to this shaft rearwardly, and which is provided with a ball bearing 89 to permit relative turning movement between shaft 71 and button 88 if it should become necessary to press button 88 inwardly while shaft 71 is rotating. Button 88 is provided with an opening 88' in alignment with opening 87'.

Gear 72 is constantly in mesh with a pinion 90 fixed on a small shaft 91 which is also slidably and rotatably mounted in wall 61 and plate 66, bearings 92 and 93 being provided to receive this shaft. A collar 94 is fixed on shaft 91 outwardly of pinion 90 so that the upper portion of this collar will bear against the outer side of the teeth on gear 72. Also fixed on shaft 91 is a gear 95 adapted upon sliding movement of shaft 91 to be moved into mesh with a drive pinion 96 which is being driven by a timer motor 97. Gear 95 may also be pushed past pinion 96 into the space between the latter and plate 66. On the hub of gear 95 a washer 98 is arranged to receive one

end of a coil spring 99 which surrounds shaft 91 and has its opposite end in engagement with a flange 100 formed on a collar 101 slidably mounted on shaft 91. Flange 100 is extended to provide a cupped end portion 102 on collar 101, which cupped portion fits over a portion of pinion 95 and bears against the inner side of the teeth on gear 72, as clearly shown in Fig. 4.

It will now be observed that when button 88 is pushed to slide shaft 71 inwardly, gear 72 which bears against collar 101 will slide shaft 91 inwardly against the action of the yielding connection provided by collar 101 and spring 99, and will move gear 95 either into mesh with pinion 96 or past the latter into the space between pinion 96 and plate 66, depending upon how far the sliding movement is carried. As long as gear 95 freely meshes with pinion 96 or goes freely past pinion 96, the yielding connection is not so important, but since pinion 96 is rotating slowly from the motor 97, it is possible for the sides of the teeth of the pinion to engage and momentarily prevent meshing of the teeth. At such time, the yielding connection is advantageous as it will prevent damage to these parts of the mechanism.

When gear 95 and pinion 96 are in mesh, shaft 71 and everything connected thereto will be slowly rotated in a clockwise direction as viewed in Figs. 2, 3 and 9, and this rotation takes place against the action of a coil spring 103 which is secured at its lower end to a projection 104 formed on the lower portion of closure member 57. The upper end of spring 103 is secured to the lower end of a steel tape member 105 which has its upper end secured to pin 13 as at 106 (see Fig. 3) whereby as gear 72 rotates, the steel tape will wind around the hub of gear 73. With this arrangement, at any time gear 95 and pinion 96 go out of mesh, spring 103 will immediately and automatically return shaft 71 and the rest of the parts operable therewith to the starting position.

When shaft 71 is moved inwardly by pushing button 88, the rear end of this shaft engages an enlarged extension 107' of Bakelite or other insulating material which is threaded on the outer end of a slidable square shaft 107, said extension being slidable in an opening formed in switch box 108'. Shaft 107 carries a movable contact member 108 of a conventional switch 109, which switch as will be later described in connection with Fig. 10, is operative when shaft 71 is in the position shown in Fig. 4 or is in its extreme inward position (see Fig. 10). Switch 109 is used to initiate the closing action of the press, as will be later described. The rear end of shaft 107 carries a collar 110 also formed of Bakelite or other insulating material and a gasket 111 is placed between the switch box and a flange 112 on collar 110. A coil spring 113 surrounds collar 110 and has one end engaging flange 112, while the opposite end of this spring extends beyond collar 110 and surrounds a small projection 114 mounted on a U-shaped bracket 115 which is secured by screws 116 to a small plate 117, said screws also securing said small plate to plate 66. This arrangement is such that rearward sliding action of shafts 71 and 107 is opposed by spring 113 and this spring will return these shafts to their initial position when push button 88 is released, provided the mechanism to be next described is not interposed in the path of movement of shaft 71 to prevent complete return movement of these shafts.

As will be observed from Fig. 4, collar 74 on shaft 71 supports a roller 118 carried on the

lower end of a rod 119 the upper end of which is pivoted by a pin 120 to a lever arm 121, intermediate the ends of the latter. The shape of lever 121 is shown in Fig. 5 and the rear wide portion of the lever is pivoted at its ends, by means of pins 122 to the free ends of bracket arms 64. Lever 121 gradually decreases in width from its rear end to its connection with pin 120, then curves for a short distance as shown in Fig. 5, and has its front portion, which passes through opening 62 in wall 61, slightly offset with respect to its pivotal connection with rod 119. The front end of lever 121 is pivoted to the lower end of a link 123 which in turn is pivoted to the lower end of a piston 124 that operates vertically in a cylinder 125 to control the passage of air to and from diaphragm valve 43. Cylinder 125 is carried by closure member 57.

From the position shown in Fig. 4, rod 119 and roller 118 are adapted, when shaft 71 is pushed rearwardly, to drop by gravity to the position shown in Fig. 8, wherein roller 118 moves into the path of forward travel of collar 74 and prevents this collar, and consequently shaft 71, from returning beyond the position shown in Fig. 8, in which position gear 95 and pinion 96 are in mesh to provide a driving connection to rotate shaft 71 and the parts secured thereto.

Rod 119 is guided in its vertical movement by means of a guide 126 preferably formed integral with and extending inwardly from the bracket arms 64. This rod passes through an opening in guide 126 and to insure movement of the rod without binding, a bearing 127 is arranged in the opening in guide 126.

Between pin 120 and the rear end of lever 121, this lever is provided with a depending portion 128 to which is secured the upper end of a leaf spring 129, the lower end of which extends into the rearward path of movement of collar 74, as shown in Fig. 4. Thus, when collar 74 is pushed rearwardly it engages spring 129, and if for any reason rod 119 has not dropped by gravity, collar 74 will tend to pivot lever 121 downwardly and thus insure downward movement of collar 118 into the path of return movement of collar 74.

Adjacent its front end, lever 121 is provided with a pair of spaced depending preferably integral projections 130 and 131 (see Fig. 6), the latter of which is longer and is adapted to act as a stop member to engage wall 61 at the bottom of opening 62 to limit the downward movement of lever 121. A pin 132 is arranged between projections 130 and 131 and this pin carries a roller 133, which when lever 121 is down as in Fig. 8, will be in the path of travel of projections on cam discs 82 and 83. The projections on the later discs will strike roller 133 and cause lever 121 to rise to the position shown in Figs. 4 and 6.

Thus, it will be seen that when rod 119 drops by gravity from the position shown in Fig. 4 to that in Fig. 8, lever 121 will move about its pivot pins 122 and also drop, since it is fastened to rod 119. Lever 121 and rod 119 will remain in their lower position until the projections on cams 82 and 83 strike roller 133 and raise both the lever and the rod back to their initial position. As soon as roller 118 on the end of rod 119 is raised to its initial position, shaft 71 and collar 74 will be moved forward by the action of spring 113, and collar 74 will again be under roller 118 so as to prevent downward movement

of rod 119 until shaft 71 is again pushed rearwardly. While I have described rod 119 and lever 121 as being adapted to drop by gravity, it will be apparent that any suitable means that will move these members downwardly at the desired time may be substituted for the force of gravity.

Referring to Figs. 4, 6 and 8, piston 124 is provided with a reduced portion intermediate its ends that forms a passageway 134 around this portion of the piston which passageway is adapted to be aligned with the various ports in cylinder 125. This cylinder is provided with an intake port 135 which communicates with the incoming air line 37, an outgoing port 136 which communicates with the outgoing line 42 leading to diaphragm valve 43, and an exhaust port 137 leading to the atmosphere. When lever 121 is up, as in Figs. 4 and 6 which show the position of the parts when vulcanization has been completed or has not been started, intake port 135 is out of communication with passageway 134 and no air can pass from incoming line 37 to line 42. However, in this position of lever 121, ports 136 and 137 are both aligned with passageway 134, whereby any air in line 42 will be permitted to exhaust to the atmosphere. When lever 121 is down, as in Fig. 8 which shows the position of the parts during vulcanization, exhaust port 137 is closed off by the piston while ports 135 and 136 are both in communication with passageway 134 to permit passage of air from line 37, through cylinder 125 into line 42 to act on diaphragm valve 43.

In passing from the incoming line 37 to port 135, air passes through port 56 in wall 55 into a small passage 138 in the wall 55 leading downwardly from port 56, then into a small port 139 which extends through a solid portion 140 of closure member 57 and through a gasket 140' arranged between closure member 57 and wall 55 so as to communicate at one end with passage 138. At its other end, port 139 communicates with an opening 141 (Fig. 6) formed in a gasket 142 arranged between closure member 57 and cylinder 125, which opening in turn communicates with port 135.

Leaving port 136, air passes through an opening 143 (Fig. 6) in gasket 142, which opening communicates with a port 144 (Figs. 4 and 8) that extends through the solid portion 140 of closure member 57 and through gasket 140', into communication with a passage 145 (Figs. 3 and 7) in wall 55 that leads to port 56' which receives line 42.

Referring now to Figs. 2 and 9 it will be seen that cam disc 81 has a cam projection 146 thereon and the front face of the disc is calibrated. In this instance there are twenty spaces each indicating one minute, and each space is subdivided into quarter minutes. Cam disc 82 has a cam projection 147 thereon which is divided into quarter minute spaces, while cam disc 83 has a cam projection 148 thereon provided with a single line 149. Fig. 2 shows the starting position of the cam discs and in this instance the time is set for nine minutes and forty-five seconds. This is accomplished by moving disc 82 until the line on the extreme left of projection 147 is in alignment with the line opposite the numeral 9 on disc 81, and then moving disc 83 until line 149 on projection 148 is in alignment with the fourth line from the left on projection 147, which represents three fifteen second spaces, or a total of forty-five seconds. The discs are

then secured in the desired position by turning bolt 87 as previously described. Ring 84 and handle 85 may be grasped when setting the discs and will facilitate this setting. With this setting 5 it will require approximately nine minutes and forty-five seconds from the time the discs begin to turn until projection 148 on disc 83 strikes roller 133 and raises lever 121 to allow shaft 71 to move forward and throw gear 95 and pinion 10 96 out of mesh, which breaks the connection to the timer motor 97. Of course, the cam discs may be set for any other desired time depending upon the length of time determined to be suitable for the cure.

15 As previously explained, shaft 71 rotates against the action of spring 103 and when gear 95 and pinion 96 are moved out of mesh, this spring will return shaft 71 and the cam discs thereon to their initial position. In order to prevent the discs going beyond their initial position, 20 a stop member 150 is arranged in the path of travel of projection 146 on disc 81, so that upon return movement of the discs, this projection 146 will engage member 150, as in Fig. 2, thus 25 insuring return of the discs to proper starting position. Stop member 150 comprises a small disc 151 secured on the end of a screw 152 which is threaded into one wall of closure member 57, and a rubber disc 153 is secured on the rear surface of disc 151 to receive the impact of projection 146 when it strikes the stop member. The 30 position of stop member 150 may be regulated by inserting a screw driver in opening 154 in the closure member 57, to engage the end of screw 35 152, and after its position is determined, it may be held against accidental displacement by means of a leaf spring 155. This spring is secured at its lower end to wall 61 about midway of opening 62 and its upper end is curved as in Figs. 4 and 8 40 to fit in any one of a plurality of notches 156 formed in the outer periphery of disc 151, thus holding the latter against accidental turning.

A front cover 157 is secured to closure member 57 by means of screws 158 and has a central opening 159 which receives a transparent glass member 160 that will permit observation of the cam discs through the glass. This glass has a central opening 161 which allows push button 88 to extend therethrough, as shown in Figs. 4 45 and 8. On the lower front portion of the device, a spring pressed stop button 162 is arranged to engage the stop switch 53 and close a circuit through this switch except when the button is held inwardly (see Fig. 10). As soon as button 50 162 is released after being held inwardly the spring is adapted to return the switch to close the circuit through this switch, as is customary in conventional switches of this type. A similar 55 spring pressed reversing button 163 is arranged to close a circuit through the reversing switch 54, but this button operates in the reverse manner of button 162, in that button 163 must be held inwardly to close a circuit through switch 60 54 and the spring returns the button to inoperative 65 position when it is released (Fig. 10).

Referring to Fig. 1, shaft 31 carries a pair of cams 164 and 165 which respectively engage a pair of rollers 166 and 167 that operate to make and break the circuits through a pair of conventional limit switches 168 and 169 (see Fig. 10) respectively. Switch 169 is not visible in Fig. 1, 70 since it is directly behind switch 168.

In the upper platen 23, a safety micro switch 192 has been arranged and this switch is operated by a pin 220 which is engaged by a lever

arm 221, pivoted at its upper end at 222 to platen 23. Intermediate its ends, lever 221 rests on a roller 223 and its lower end is secured to an arcuate bar 224 which extends in front of the press and partially to the sides thereof, but which is in a position that will not interfere with the normal closing and opening of the press. However, should an operator's arm or any other obstruction be in the path of the upper press head during its closing movement, bar 224 will strike the obstruction and cause lever 221 to pivot upwardly against pin 220, thus throwing switch 192 to a position which will break the circuit therethrough and immediately stop the press from further closing. As will be later explained, this movement of safety switch 192 also closes a reversing circuit which causes the press head to return to its starting position.

At times it may be necessary to remove the cam discs 81, 82 and 83 from shaft 71 to permit replacement or repair, etc. After removal of these discs, spring 103 will tend to rotate shaft 71 beyond its proper position, and to prevent this rotation I place a small projection 225 on the rear face of gear 12 which acts as a stop member and engages collar 100 to prevent rotation of shaft 71 beyond the point determined to be proper.

Fig. 10 shows a wiring diagram of the circuits used with this device and to assist in better understanding the operation, certain of the parts have been illustrated in conjunction with this diagram. The circuits to be described are preferably intended for use with alternating current, although direct current may be used if desired. Numeral 170 indicates a main switch having three arms 170a, 170b, 170c, which is interposed between a source of current, in this instance of about 440 volts, and the circuits to be described. When arm 170a is in the dotted line position it is connected to a conductor 171 leading to a transformer 172, used to step part of the current down to about 110 volts. Transformer 172 is in turn connected to conductor 173 leading to arm 170b, which in its dotted line position completes the circuit through the transformer. From the transformer 172, a conductor 174 leads to arm 52a of the double switch 52, which in the full line position, is connected to conductor 175 which leads to stop switch 53, which is always closed until button 162 is pushed to break the circuit. From switch 53 a conductor 176 leads to conductor 177 which in turn leads to limit switch 169 which is in its full line position when the press is open. From the full line position of switch 169, a conductor 178 leads to the rear position of the starting switch 109, shown in dash lines. When switch 109 is in the rear position it is connected to a conductor 179 which in turn is connected to a conductor 180, and the latter leads to a coil 181 of a relay comprised of said coil and four switch contactors 182, 183, 184 and 185. From coil 181 a conductor 186 leads to a conductor 187 which leads back to transformer 172 to complete the circuit. It will be seen that in order to make this circuit operative, it is only necessary to push shaft 71 rearwardly to its extreme rearward position whereby switch 109 will engage conductors 178 and 179.

Conductor 174 is also connected to a conductor 188 leading to arm 52b of switch 52, which in the full line position is connected to a conductor 189 leading to the timer motor 97. From motor 97 a conductor 190 leads to conductor 187 which is connected to the transformer 172. Thus when

switch 52 is in the full line position, a circuit is completed through timer motor 97 to start the latter in operation, and a second circuit through coil 181 is ready to be completed as soon as switch 109 is moved to its dash line position.

When coil 181 becomes energized by the circuit passing therethrough as described, the switch contactors 182, 183, 184 and 185 are closed and remain closed until the circuit to the coil 181 is broken. Since the rear position of switch 109 is obtained only while button 88 is being held at its full inward position, it becomes necessary to provide a holding circuit which will preserve the circuit through coil 181 after the button 88 is released. This holding circuit is obtained by having switch 168 in its dotted line position just as the press starts to close, whereby its lower terminal is connected to conductor 177 leading to conductor 176. The upper terminal of switch 168 in its dotted line position is connected to a conductor 191 leading to safety switch 192, which is in its full line position at this time. From the safety switch 192, a conductor 193 leads to contactor 182 which, being closed makes a connection through conductor 194 to conductor 180 and thence to coil 181 to complete the circuit through coil 181 without regard to starter button 88.

Motor 32 is a conventional three phase motor and the three circuits leading thereto are as follows:

Going back to switch arm 170a, a conductor 196 leads to contactor 183, which being closed, makes a connection through conductor 197 to point 198 on the press motor 32. The second circuit leads from point 199 on motor 32, through conductor 200 to contactor 184, which being closed, makes a connection to conductor 201 which leads to arm 170b of the switch 170 in its dotted line position. Referring now to the third circuit, from switch 170c in its dotted line position, a conductor 202 leads to contactor 185, which being closed, makes a connection to conductor 203 which leads to point 204 on motor 32.

After the press motor is started the press begins to close and the holding circuit is broken as soon as the press is closed by having cam 164 engage roller 166 and move switch 168 to its full line position. This opens contactors 182, 183, 184 and 185 and consequently breaks all circuits which included these contactors, thus shutting off the press motor 32. At this point, however, the timer motor 97 is still in full operation since the circuit thereto has never been broken.

During the closing movement of the press if an operator's hand or arm engages the bar 224 which throws safety switch 192, this switch will move to the dotted line position and break the circuit to coil 181, thus stopping the press motor 32. At the same time a reversing circuit is made through the dotted line position of switch 192 to conductor 205, then to conductor 206 which leads to one side of a reversing coil 207 of a relay which is comprised of said coil and switch contactors 208, 209 and 210. The other side of coil 207 is connected to a conductor 186 leading to conductor 187 which is connected to transformer 172. When coil 207 is energized by the circuit passing therethrough, contactors 208, 209 and 210 are closed to make circuits through them. Since a three phase motor may be reversed by reversing any two of the three circuits leading to it, the reversing circuits are now complete and the first circuit comprises arm 170a leading to conductor 196 which in turn leads to conductor 211 connected to contactor 209, the latter also

being connected to conductor 200 which leads to point 199 on motor 32. The second reversing circuit is from point 198 on motor 32 which is connected through conductor 197 to contactor 208, and the latter is connected through conductor 212 to conductor 201, which leads to arm 170b. It is not necessary to reverse the third circuit and the latter comprises arm 170c connected through conductor 202 to conductor 213 which leads to contactor 210, the latter being connected to conductor 203 which leads to point 204 on motor 32.

The closing movement of the press may also be stopped by pushing stop button 162 inwardly against the action of its spring to break the circuit through switch 53. This results in breaking the circuit through coil 181, which opens contactors 182, 183, 184 and 185 and stops the press motor 32.

After the closing of the press has been stopped by pushing button 162, the movement may be reversed by pressing the reversing button 163 to close a circuit through conductors 206 and 214. When the reversing switch 54 is in reversing position it is connected by conductor 214 to switch 168 in the broken line position of the latter, and by conductor 206 to coil 207 which results in reversing motor 32 in the same manner described when safety switch 192 was thrown to its dotted line position. When reversing switch 54 is in the circuit, the latter comprises transformer 172, conductor 174, arm 52a of switch 52, conductor 175 and switch 53. This switch 53 will be returned to circuit closing position as soon as the button 162 is released after the press is stopped. Switch 53 is connected through conductor 176 to conductor 177 which leads to the lower terminal of switch 168, the latter being connected in its dotted line position to conductor 214.

In the final movement of the closing of the press, in addition to breaking the holding circuit by moving switch 168 to its full line position, cam 165 engages roller 167 and throws limit switch 169 to its dotted line position. Since the cycle of operations, unless interrupted as described, is entirely automatic after the press is started by pushing button 88, it is necessary that the press open automatically after vulcanization is complete. As previously explained, cam 83 will strike roller 133 at the end of the cure and raise roller 118 so that shaft 71 can return to its initial position. In this initial position, switch 109 is in the full line position and closes a circuit through conductors 180 and 215. This will energize coil 181 and start the press motor 32 in operation to open the press. This circuit is from transformer 172 through arm 52a of switch 52, conductor 175, switch 53, conductors 176 and 177, switch 169 in its dotted line position, conductor 215, switch 109 in its full line position, conductor 180, coil 181, and conductors 186 and 187 to the transformer 172. Thus coil 181 will be energized again and contactors 182, 183, 184 and 185 will be closed to complete the circuits to motor 32 in the manner previously described.

As soon as the press is fully open, roller 167 drops off of cam 165 and allows switch 169 to return to its full line position, breaking the circuit to coil 181 and stopping the motor 32.

To better understand the complete operation the various steps will be reviewed in their logical order. A tube 13 is first placed in the lower mold section 10, connected to fluid line 16 and discs 81, 82 and 83 are set for the desired time of cure to be given to the tube. At this time the

diaphragm valve 43 is closed so that fluid cannot enter tube 13 and valve 38 is closed so that air cannot pass beyond the latter valve in line 37. The main switch 170 is now moved so that its arms 170a, 170b and 170c are in their dotted line positions and switch 52 is moved (by moving handle 52' to the right in Figs. 2 and 3) so that its arms 52a and 52b are in their full line positions. This action starts the timer motor 97 in operation through arm 52b and prepares the circuit through arm 52a to coil 181 so that the latter will be energized when switch 109 is moved to its dash line position.

The press is now ready for operation and the starting button 88 is pushed inwardly as far as it will go to slide shaft 71 to its extreme rearward position and move switch 109 to its dash line position. This sliding movement of shaft 71 moves gear 95 past pinion 96 and into the space between the latter and plate 66, and the press begins to close as soon as switch 109 closes the circuit through coil 181 and starts motor 32 in operation. The initial closing movement of the press moves switch 168 to its dotted line position, which closes the circuit through the holding circuit and permits button 88 to be released without de-energizing coil 181.

Also, when shaft 71 was moved rearwardly, roller 118 dropped into the path of collar 14 and will prevent return movement of shaft 71 beyond roller 118. Shaft 71 and switch 109, therefore, remain in an intermediate position which is shown by the dot and dash position of switch 109 on Fig. 10. When roller 118 dropped downwardly, lever 121 also dropped to its lower position and permitted communication between ports 135 and 136 of the piston valve, so that when air passes into cylinder 125 from line 37, it is free to pass out through line 42 to diaphragm valve 43. But, at this time air cannot pass beyond valve 38 in line 37 because the latter valve has not yet been opened.

Roller 118 is adapted to permit return movement of shaft 71 to a position where gear 95 and pinion 96 are in mesh and to hold this position until the cure is complete. Hence, when button 88 is released, gear 95 and pinion 96 will be allowed to mesh to provide a driving engagement from motor 97 to shaft 71, to rotate the latter and the cam discs secured thereon. Since this driving connection will be made before the press is closed and before any curing medium is admitted to tube 13, it is necessary, in setting the cam discs 81, 82 and 83 to make allowances for the time during which the discs will be rotating before the cure actually starts.

As the press reaches its final closing movement, switch 168 is moved to its full line position to break the circuit to motor 32 and stop the press, and switch 169 moves to its dash line position to prepare the circuit which will open the press after the cure is complete.

When link 19, which carries pin 41, reaches the broken line position in Fig. 1, the press is closed and plunger 41 engages pin 40 and remains in engagement therewith to open valve 38 to admit air to cylinder 125. Since lever 121 is in its lower position, air will pass through cylinder 125 to line 42, which air acts on diaphragm valve 43 to open the latter and admit the curing medium from line 44 into tube 13.

When the cam discs have been rotated nearly the distance previously determined to be proper, projection 141 will strike roller 133 on lever 121 and raise the latter a short distance which is suffi-

cient to shut off the flow of air through cylinder 125, thus cutting off the supply of air to the diaphragm valve 43. This action also places the exhaust port 137 of cylinder 125 in communication with line 42 and allows the air which was acting on valve 43 to be exhausted to the atmosphere. Thus valve 43 is closed again to cut off the curing medium to tube 13, and this curing medium is allowed to exhaust to the atmosphere through the exhaust port in valve 43. The movement upwardly of roller 118 at this time is not enough to permit return of collar 74, as shown in broken lines in Fig. 8. At the time projection 147 strikes roller 133 about 45 seconds remains until this roller will be engaged by projection 148 which will raise lever 121 to its full upward position. Thus air is allowed to exhaust from the tube about 45 seconds ahead of the opening of the press.

At the time lever 121 is moved fully upwardly, rod 119 and roller 118 are also moved upwardly whereby shaft 71 may return to its initial position, in which position switch 109 assumes its full line position and closes the circuit which starts the press to open. At the completion of the opening movement of the press, switches 168 and 169 return to their initial positions, breaking the circuit to motor 32 and preparing the circuits for the next cycle of operation. When shaft 71 returns to its starting position, gear 95 is moved out of engagement with pinion 96, and spring 103 will immediately rotate shaft 71 in the opposite direction, thus returning discs 81, 82 and 83 to their initial positions. During the opening movement of the press plunger 41 becomes disengaged from pin 40 and valve 38 is closed until the press again closes during its next operation. Thus all the parts are returned to their initial positions, the vulcanized tube is removed from the press and the latter is ready for another operation.

The operation of the safety mechanism has already been described as well as the functions of the stop and reverse buttons and need not be repeated.

In Fig. 2 it will be noted that handle 52' of switch 52 can be moved to the left to what is termed the manual position, as well as to the automatic position to the right. As shown in Fig. 10, this manual position is represented in broken lines and merely results in cutting out the circuit to the timer motor 97 so that the device no longer works automatically.

There are several additional features present in this invention, some of which I will call attention to. For example, it is possible to release shafts 71 and 91 at any time before the completion of the cure, and upon their release, the spring 103 will return them to their initial position. This release is accomplished by pushing button 88 inwardly to slide shafts 71 and 91 from the position shown in Fig. 8 to a position where gear 95 is out of mesh with pinion 96 and is between the latter and plate 66. As soon as this gear and pinion go out of mesh and no restraint is placed on shafts 71 and 91, spring 103 will reverse the rotation of these shafts and return them to starting position.

It sometimes is desirable to stop the closing of the press before it has completed its closing movement and this can be done by pressing stop button 162. After stopping this closing movement, the timing mechanism can be returned to starting position by sliding shafts 71 and 91 as previously explained until gear 95 and pinion 96 are out of mesh. In this same sliding movement

of these shafts, if shaft 71 is pushed completely inwardly, switch 109 will again close the circuit in its broken line position and the press will continue its closing movement with the timing mechanism starting from its initial position. This may result in a few seconds additional cure to compensate for the time which elapsed before the press was stopped in its closing movement, but these few seconds do not appreciably affect the cure.

After the cam discs have started their rotation with shaft 71 it is possible to increase or decrease the length of time for the cure. Suppose, for example, the timer has been running for about five minutes and it is desired to increase the time of cure for an additional four minutes. Shafts 71 and 91 are now slid rearwardly by placing a conventional hexagonal key (not shown) in the hexagonal opening 87' formed in nut 87, and pushing this key rearwardly. This action will cause gear 95 and pinion 96 to go out of mesh, but the shafts 71 and 91 cannot be rotated by spring 103 as long as the key is held in the operator's hand. With the gear and pinion out of mesh, shaft 71 and the cam discs thereon may be turned back to one minute by turning the key. Thus, when the shafts 71 and 91 are permitted to return to the Fig. 8 position with the gear and pinion in mesh it will take four additional minutes to complete the cure.

Similarly, if the curing time is to be shortened, for example for a period of two minutes, after five minutes has already elapsed, the key is turned to bring the shaft 71 and the cam discs thereon forward two minutes. Thus, when the gear and pinion are then allowed to return to their meshed position, it will require two minutes less time to complete the cure.

While I have shown and described the preferred form of the invention it will be apparent that modifications may be made therein without departing from the spirit of the invention or from the scope of the subjoined claims.

What is claimed is:

1. In combination with a vulcanizing press of the character described, mechanism for opening and closing the press, means for supplying a curing medium to an article in said press comprising a fluid pressure line, a pair of spaced valves in said line, means for opening one of said valves in advance of the other valve, time controlled means for closing said one valve at a predetermined time in advance of the other valve, and means carried by the press opening and closing mechanism for opening the other valve as the press is closed and for closing said other valve as the press is opened.

2. In a press of the character described, the combination with a chamber and mechanism for closing and opening the chamber, of time controlling mechanism operative to determine the period during which the chamber remains closed, means for initiating the movement of said mechanism for closing the chamber and for starting said time controlling mechanism, means for arresting said closing movement before it is complete, means including said first named means for returning said time controlling mechanism to its initial position after the closing movement of the press has been arrested, said first named means being operable thereafter to again start said time controlling mechanism and continue the closing movement of the press.

3. In a press of the character described, the combination with a chamber and mechanism including an electric circuit for closing and open-

ing the chamber, of time controlling mechanism including a motor operative to determine the period during which the chamber remains closed, means for initiating the movement of said mechanism for closing the chamber and for starting said time controlling mechanism comprising a rotatable shaft movable longitudinally to close said electric circuit and into driven engagement with said motor whereby said motor will rotate said shaft in one direction, a member operable to rotate said shaft in the opposite direction, means for arresting said closing movement before it is complete, and means including said first named means to make said member operable to rotate said shaft in the opposite direction to return said time controlling mechanism to its initial position and thereafter to again start said time controlling mechanism and continue the closing movement of the press.

4. In a press of the character described, the combination with a curing chamber and mechanism for closing and opening the chamber, of time controlling mechanism operative to determine the period during which the chamber remains closed, means for initiating the operation of said mechanisms to close the chamber and for starting said time controlling mechanism, said means being operable to arrest the action of said time controlling mechanism before the completion of the cure, and means cooperating with said first named means to thereafter restore the action of said time controlling mechanism.

5. In a press of the character described, the

combination with a curing chamber and mechanism for closing and opening the chamber, of time controlling mechanism operative to determine the period during which the chamber remains closed, means for initiating the operation of said mechanisms to close the chamber and for starting said time controlling mechanism, said means being operable to arrest the action of said time controlling mechanism before the completion of the cure, means for returning said time controlling mechanism to its starting position after its action has been arrested, and means cooperating with said first named means to thereafter restore the action of said time controlling mechanism.

6. In a press of the character described, the combination with a curing chamber and mechanism for closing and opening the chamber, of time controlling mechanism operative to determine the period during which the chamber remains closed, means for initiating the operation of said mechanisms to close the chamber and for starting said time controlling mechanism to operate for a predetermined curing period, said means being operable to arrest the action of said time controlling mechanism before the completion of the cure, means for resetting the time controlling mechanism after its action has been arrested to change said predetermined curing period, and means cooperating with said first named means to thereafter restore the action of said time controlling mechanism.

LESLIE E. SODERQUIST.
